UNITED STATES PATENT OFFICE.

ERNEST THEODORE FRANZEN, OF JAMAICA, NEW YORK.

AUTOMATIC RAIL-LUBRICATOR.

1,311,505.

Specification of Letters Patent. Patented July 29, 1919.

Application filed February 19, 1919. Serial No. 277,960.

To all whom it may concern:

Be it known that I, ERNEST THEODORE FRANZEN, a subject of King Gustavus V of Sweden, and a resident of 58 Glenmore 5 Boulevard, Jamaica South, in the county of Queens and State of New York, have invented certain new and useful Improvements in Automatic Rail-Lubricators, of which the following is a specification.

10 This invention relates to rail lubricators, and especially to that class of lubricators which is carried as a permanent fixture beneath a car and derives the necessary pressure for applying the lubricant from an air 15 tank.

It is the object of this invention to lubricate the inner face of the outside rails on railroad curves by employing the changed relative positions of the car truck and the 20 body as an automatic means of opening the lubricant valves and causing the lubricant to be applied through suitable means herein described.

Referring to the drawings, like numerals 25 refer to the same parts throughout the views.

Figure 1 is a plan view of a model car truck equipped with an apparatus embodying the present invention, with a portion of tank 27 and valve parts 7 and 8 in section 30 to expose the interior. Fig. 2 is a side view of Fig. 1. Fig. 3 is a plan view of a modification of the invention, with only essential parts shown. Fig. 4 is an enlarged front view of grease shoe 1 and its related parts 35 as illustrated in Figs. 1 and 2. Fig. 5 is a considerably enlarged side view of the same grease shoe 1 with a section of its supporting bar 10. Fig. 6 is a view of the oil brush that sets into recess 37 of Fig. 5.

40 It is well known that upon railroads generally there is a tremendous wear and tear mutually inflicted upon the outer rails of curves on the said roads and the wheel flanges of the rolling stock. This has become 45 doubly true in the last twenty years because of the increase in the weight of rolling stock and the great speed of modern traffic.

It is with the end in view of practically eliminating this troublesome problem and its 50 attendant expense that the present invention has been designed.

A Lubricant tank 27 is secured to a car body as partially indicated by dotted lines at 55 and likewise brackets 24 and 25, and is furnished rearwardly with petcock 26 and air valve 14 which connects directly to the

air brake system on the car. On either side of the tank are situated valves 7 and 15, both of which have their pistons connected to and actuated by a rocking cam plate 9 which is 60 provided with a pair of corresponding slots on either side, the stud of piston 8 engaging slot 8'. The plate 9 is centered at 3 upon the forward end of tank 27 and contains further a long slot 9'. The truck 19 has extending from its crossbeam 6 a cam rod 11 whose stud engages and is adapted to slide in slot 9' of plate 9. The position of the truck as shown on the straight rails 20 and 21 leave the entire apparatus inactive. However, the 65 forward journals 18 and 22 support pendant grease applicators adapted to slide against the inner faces of rails 20 and 21. The mounting of one of these grease shoes 1 is made more clear in Figs. 4 and 5, the pivot 29 70 permitting shoe 1 to swing slightly as the shape of the cross bar which supports the two applicators limits the swing of the grease applicator or shoe, an added spring 30 insuring contact between the shoe and the 75 rail. The valves 7 and 15 are connected to the grease shoes on their respective sides by flexible tubes 4 and 5, permitting the truck 19 to turn without any obstruction.

If the truck 19 were to be run up on a 80 curved track as indicated at 16 and 17, the cam bar 11 would change its position to that indicated at 12, and would draw the cam plate 9 into a position indicated at 13 because of the form of slot 9'. This would 85 draw piston 8 into open position in valve 7, and as there is considerable air pressure in the chamber to the right of blind piston 2 in tank 27, the grease in the chamber to the left would be forced out through tube 4 90 to shoe 1 and from the same applied along the inner face of the outside rail 16 until a straight track is again reached. The inside rail 17 receives no grease, and it is thus seen that the apparatus is entirely automatic in 95 operation.

When the grease is exhausted from tank 27, valve 14 is closed, and petcock 26 opened. This releases the air in the tank. The plug 100 28 is then removed and a grease gun or container connected to the aperture and grease forced into the tank under pressure. Then plug 28 is replaced, petcock 26 closed and valve 14 opened, and the apparatus is again 105 in order. In Figs. 5 and 6 will be seen more 110 particularly the details of grease applicator 1. The nipple 4' is the anchorage for the

grease tubing 4, the grease passing down through indicated channel 36 and out through aperture 1'. However, in order to properly spread the grease, a ring brush 38 is secured in the recess 37 by friction or other means, the bristles of the brush engaging the rail directly, the nose of the shoe being really only a guide and protection for the brush. The latter is, of course, easily renewable when worn out.

In Fig. 3 another form of my invention appears. The cam bar 11 has here been replaced by a bar 33 which bears a roller 32 in contact with a cam plate 31. The tank 27 is only indicated and likewise its valves by dotted lines. If the cross beam 6 were to turn clockwise upon its axis the cam bar 31 would assume a position indicated at 40 and the cam plate would rock into a position seen at 39. This would push valve rod 34 into open position while it would pull rod 35 in the opposite direction. It is clearly evident that this operation though opposite to the operation of the other form described is identical in result and is really exactly the same in principle.

Likewise, a single valve alone being operated by a rocking cam plate would be identical with my invention, and doubling this, or having two valves and an individual plate for each while employing the same cam bar would still be the same principle.

Having thus fully described my invention, I desire to obtain by United States Letters Patent.

1. A rail lubricator including a lubricant container, a valve upon one portion thereof, a piston extending from said valve, a rocker cam plate centered upon a portion of said container and provided with a portion adapted to engage the piston rod of said valve, and a cam bar adapted to engage portions of said cam plate to move the same and open said valve by moving said piston, said cam bar and said container being respectively secured to a truck and the body of a railway car.

2. A rail lubricator including a car with

swiveling trucks, a cam rod extending from one of said trucks under the body of said car, a lubricant container rigidly secured to said car provided with air valves upon one end with a pair of grease outlet valves upon the other end, a rocker cam plate centered in a portion of said container and engaged by said cam rod, valve pistons in said grease valves directly connected to said cam plate and tubes connecting said valves with grease applicators situated upon the said truck.

3. A lubricator including upon a car truck an extension provided with a swing grease applicator and limits upon said extension formed by the sides of said extension or bar in the proximity of the pivot of the grease applicator to limit the radius of action of said applicator, and a nose upon the forward portion of said applicator.

4. A rail lubricator including upon the truck of a car an extension bearing a rocking member held thereby in contact with the inner face of the rail adjacent thereto, and a spring secured upon said extension and tensed against said rocking member to insure contact between the latter and the rail.

5. A rail lubricator including a rail wiping member mounted upon a car truck and adapted to lie against a side face of a rail beneath said car, and a ring brush situated in a recess in said member and surrounding said grease outlet and contacting with said rail.

6. A grease applicator for railways including an elongated pendant body pivoted at one end and provided at the other end with a forwardly extending pointed portion and upon the side of said latter end with a grease vent.

Signed at 132 Nassau street, in the borough of Manhattan, county of New York, city and State of New York this 18th day of February, 1919.

ERNEST THEODORE FRANZEN.
